[57] **CLAIM**

The ornamental design for an automobile body, as shown and described.

DESCRIPTION

FIG. 1 is a front view of an automobile body according to our novel design;

FIG. 2 is a right side view of an automobile body according to our novel design;

FIG. 3 is a left side view of the automobile body of FIG. 1 according to our novel design;

FIG. 4 is a rear view of the automobile body of FIG. 1 according to our novel design; and,

FIG. 5 is a top view of the automobile body of FIG. 1 according to our novel design.

The broken lines showing of the side mirrors, wheels and other features are only for showing the surrounding environment and are not a part of the claimed design.
